UNITED STATES PATENT OFFICE.

ISAAC WANTLING, OF PEORIA, ILLINOIS.

COAL OR ROCK DRILL.

SPECIFICATION forming part of Letters Patent No. 683,628, dated October 1, 1901.

Application filed June 8, 1901. Serial No. 63,717. (No model.)

To all whom it may concern:

Be it known that I, ISAAC WANTLING, a citizen of the United States, residing at Peoria, in the county of Peoria and State of Illinois, 5 have invented certain new and useful improvements in Coal or Rock Drills; and I do hereby declare that the following is a full, clear, and exact description of the invention, which will enable others skilled in the art to 10 which it appertains to make and use the same.

This invention has reference to coal or rock drills, and especially to that class of drill known as a "grip-drill."

The object which I have in view is to provide a drill comprising a boxing of two hinged sections with a depending semicircular body portion, having a notched edge, and a grip-bar attachment having a pivotal relation with the lower section of the hinged boxing and 20 supporting a grip-bar arranged to be locked to said attachment.

The invention consists, further, of an anchor, to which the forward end of the grip-bar may be detachably secured for supporting the 25 same, said anchor purposed to be first driven into the material to be worked and then attaching the grip-bar thereto, forming a support for the drill and holding the auger thereof to its work.

30 The invention consists in various details of construction and arrangement of parts hereinafter more fully described, and pointed out in the appended claims, due reference being had to the accompanying drawings, forming a 35 part of this specification, in which—

Figure 1 is a drill, shown in elevation, embodying my improvements. Fig. 2 shows a plan, enlarged, of the boxing and grip-bar attachment. Fig. 3 is an elevation of Fig. 2. Fig. 4 is a side elevation of one side of Fig. 40. Fig. 5 shows a cross-section of the grip-bar attachment. Fig. 6 is a perspective view of the anchor. Fig. 7 is a cross-section through the same, showing certain details; and Fig. 45 8 is an elevation, partly in section, of the support for the rear end of the grip-bar.

In the drawings like numerals refer to corresponding parts throughout the figures.

The drill comprises two half-boxings 1 and 50 2, hinged together at 3, the nut thereof formed of semicircular threaded linings suitably secured in the half-boxings. The boxing 2 has

the laterally-extended arm 4 with tubular bearing 5 arranged to support power mechanism, which comprises a stem journaled in 55 the bearing carrying a bevel-gear 6, intermeshing with a bevel-gear 7, carried by the thread-bar 8, and 9 is a crank for actuating the thread-bar through such power mechanism.

Depending from the lower half-boxing I provide a semicircular extension 10 and a tubular bearing 11, said bearing arranged transversely to the movement of the thread-bar, and 12 is an aperture therein. This semicircular extension 10 of the boxing is arranged in an arc whose radius is struck from the center of the aperture 12, and the lower edge or face of the extension is provided with notches, as 13, which are substantially V-shaped for 70 a purpose to be described.

14 is a yoke having a rectangular body portion 15, with a rectangular opening 16 through the same, and 17 shows diverging arms of the yoke with apertures 18. This yoke is arranged to span the extended and flared portion of the lower half-boxing and be attached thereto by means of a pin or similar device, which is slipped through the apertures 18 and tubular bearing 11 of the boxing. The yoke 80 is designed to carry a grip-bar 19, which in this instance is a hollow rectangular bar in size adapted to fit snugly the rectangular opening 16 in the yoke, and one edge of the bar is provided with a series of serrations 20, 85 as shown. Thus it is that when the bar is slipped through the opening 16 and the yoke is made to span the lower half-boxing, substantially as is illustrated in Fig. 3, a yoke-pin 21, having the portions 22 and 23, is used 90 for locking not only the yoke to the boxing, but the grip-bar to the yoke. The extension 22 of the yoke-pin 21 is slipped through the extensions 17 and tubular bearing 11, and the extension 23 of said pin is slipped through 95 an aperture 24, arranged in the yoke, which cuts through the rectangular body in such a manner that the pin 23 will engage a serration of the grip-bar and a notch in the lower edge of the semicircular extension of the 100 boxing. The extension 23 of the yoke-pin in cross-section has the rounded lower portion 25 and the V-shaped upper portion 26. This arrangement will permit of a greater number

of notches in the extension 10 than could be provided by the use of serrations such as used in the grip-bar and permit of the drill being adjusted to a greater number of positions.

27 refers to an anchor-shoe having the tapered or wedge portion 28 and the portions 29 and 30, the portion 30 extending beyond the body portion 29 a suitable distance and provided with a rectangular socket 31 therein, and 32 is an aperture passing through the anchor, as shown. In drilling coal or other material it is necessary to support and brace the grip-bar in a positive manner. This has been done heretofore in various ways; but I am not aware that an anchor of the character described has ever been used which may be first driven into the material and then fastening the grip-bar to the same. This is accomplished as follows: The provision of the wedge makes it easy to hammer it into the coal or rock, and the provision of the offset 29 of the anchor provides a seat by which the same may be hammered into the material, and when securely fastened therein the end of the grip-bar may be inserted into the socket 31 of the extension 30, and the bar having an aperture 33 through the same a pin or similar device 34 is dropped through the aperture 32 and through the aperture 33 of the bar, which locks it firmly to the anchor. While I have shown that the grip-bar is detachably connected to the anchor by being inserted in the notch 31, it is to be understood that the extension 30 may be so arranged that it may be inserted into the grip-bar and locked instead of the bar being inserted into the socket 31.

The manner of coupling the boxings and yoke makes it possible to shift the boxing and drill-rod to any angle coming in range of the movement of the semicircular extension thereof. As it will be seen, the grip-bar is firmly secured in the coal or rock. By releasing the yoke-pin, so that the extension 23 is free of the yoke and boxing, the drill-rod may be moved to a suitable angle, as the boxing is free to swing on the extension 22 of the yoke-pin, and when in position the extension 23 may be again made to engage the aperture 24 and the yoke and corresponding notch in the semicircular extension of the boxing, which locks the parts firmly together in the manner shown.

55 By supporting the drill on a bar of the character shown it has the advantage after the thread-bar has been advanced in the feed-nut its length to open the upper section of the hinged boxing and advance the boxing on the grip-bar until the nut again engages the forward end of the threaded bar and the drill is in position to advance the auger its full length into the coal or rock when adjusted at proper angles.

65 I have provided a novel support for the rear end of the grip-bar, which comprises a support 35, having a rectangular bearing 36

to be slipped over the rear end of the bar in the manner shown in Fig. 1 and tied to the same by means of a pin 37 or similar device, 70 passing through an aperture 38 in the support and a serration of the bar, and extending down from the bearing is shown a perforated bar or rod 39, telescoping into a support 40, with bifurcated extensions 41, the same held in adjusted positions on the bar 39 by a pin 42, passing through the support 40 and bar 39.

Diverging from the upper face of the bearing 36 is shown a frame of bifurcated sections 80 42, arranged to straddle the thread-bar and centering into a common spindle 43, which is threaded and provided with a hand-wheel 44, and telescoping onto the spindle is a movable section 45, adjustable by the movement 85 of the hand-wheel, substantially as shown in the drawings.

I do not wish to be limited to the details of construction and arrangement of parts as herein described and illustrated, as it is obvious that various changes may be made in the construction of parts as to details without affecting the principle and scope of invention herein.

Having thus fully described my invention, 95 what I claim, and desire to secure by Letters Patent of the United States, is—

1. A drilling-machine, comprising a boxing of two hinged sections, a semicircular extension of one section, a member pivotally connected with the boxing and a grip-bar adjustably secured in said member and means of locking said grip-bar and said semicircular extension, substantially in the manner described. 100

2. A drilling-machine, comprising a boxing of two hinged sections, a semicircular extension of one section and an aperture transversely arranged therein, a member provided with a rectangular body and diverging arms 110 pivotally fixed to the boxing, a grip-bar engaging the rectangular body of the member and means for connecting the member and boxing and locking the bar to the rectangular body, substantially as described. 115

3. A drilling-machine, comprising a two-part boxing, having a feed-nut, a semicircular extension of the boxing having a serrated edge, a transverse aperture through the extension, of a member, having flared extensions straddling the serrated extension of the boxing and a rectangular body portion, a grip-bar arranged to be carried in the rectangular body of the member and a yoke-pin for locking the member to the boxing and the bar to the member, substantially as described. 120 125

4. A drilling-machine, comprising a feed-nut substantially as shown, a semicircular extension of the nut provided with a notched edge, and a transverse aperture therein, a member provided with a rectangular body straddling the semicircular extension and an aperture cutting through the rectangular

body, a grip-bar arranged to be carried in the rectangular body of the member and a yoke-pin the extensions of which are arranged to couple the member to the feed-nut and engage the aperture of the rectangular body and serrations of the bar and coincident notch of the extension of the feed-nut, substantially as described.

5. A drilling-machine, comprising a feed-nut, a member comprising a rectangular body and diverging arms straddling the feed-nut and pivotally connected to said feed-nut, a grip-bar adjustably secured in said rectangular body, an anchor for the forward end of the bar and means of connecting the bar to the anchor and the means for supporting the opposite end of the bar, substantially as described.

10. In combination with a two-part boxing and a feed-nut, a thread-bar and mechanism

for actuating said bar, a grip-bar support for said feed-nut, comprising a bar having one edge serrated, a member slidably arranged on the bar and having connection with an extension of the feed-nut having a serrated 25 edge and in such a manner as to permit the nut to swing in its support, a device for locking the member and bar through the serrations in the bar and said extension, an anchor-support detachably connected with the 30 forward end of the bar, and adjustable supporting means substantially as shown for the rear end of said bar, substantially as described.

In witness whereof I affix my signature in presence of two witnesses.

ISAAC WANTLING.
